US00D883940S

(12) **United States Design Patent** (10) Patent No.: **US D883,940 S**
(45) Date of Patent: **** May 12, 2020**

(54) **CIRCUIT BREAKER**

(71) Applicant: **ABB S.p.A.**, Milan (IT)

(72) Inventors: **Lucio Azzola**, Bergamo (IT); **Stefano Besana**, Terno d'Isola (IT)

(73) Assignee: **ABB S.p.A.**, Milan (IT)

(**) Term: **15 Years**

(21) Appl. No.: **29/698,680**

(22) Filed: **Jul. 18, 2019**

Related U.S. Application Data

(62) Division of application No. 29/655,704, filed on Jul. 6, 2018, now Pat. No. Des. 858,460, which is a division of application No. 29/605,137, filed on May 24, 2017, now Pat. No. Des. 823,816, which is a division of application No. 29/532,336, filed on Jul. (Continued)

CLAIM

The ornamental design for circuit breaker, as shown and described.

DESCRIPTION

FIG. 1 is an isometric view of an embodiment of the new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line portion of the figure drawings are included to illustrate portions of the circuit breaker that form no part of the claimed design.

1 Claim, 7 Drawing Sheets
